UNITED STATES PATENT OFFICE.

CARL ERIC ANDERSON, OF STRATFORD, CONNECTICUT, ASSIGNOR TO THE BRYANT ELECTRIC COMPANY, OF BRIDGEPORT, CONNECTICUT, A CORPORATION OF CONNECTICUT.

ELECTRIC SWITCH.

Application filed December 22, 1921. Serial No. 524,215.

To all whom it may concern:

Be it known that I, CARL ERIC ANDERSON, a citizen of the United States of America, residing at Stratford, in the county of Fairfield and State of Connecticut, have invented certain new and useful Improvements in Electric Switches, of which the following is a specification.

My invention relates to electric switch, 10 and particularly to snap switches of the type commonly used in control lighting circuits. Among the objects of my invention may be noted, first, the provision of a narrow and shallow structure, of high current-breaking capacity, well adapted for workmanlike installation in locations where a deep bodied switch cannot be well used, for example in thin partition walls, in moldings, etc.; second, a reduction in manufacturing costs by the use of few parts, readily struck and formed up from sheet metal, the assembly of the switch mechanism being readily performed by hand and being self-sustained in assembled condition; third, the 20 provision of not only an effective snap action for the moving parts of the switch, but also positive initiation of the throw of the switch blades to open-circuit position; fourth, various features of novelty and improvement in details of construction, assembly and operation hereinafter described or shown in the accompanying illustrative drawings, in which—

Fig. 1 is a broken plan view of a switch 30 in which my invention is embodied in one form;

Fig. 2 is a section on the line 2—2, Fig. 1;

Fig. 3 is an inverted plan view of the 40 switch body;

Fig. 4 is a perspective view of the insulating cover for the switch chamber;

Fig. 5 is a detached perspective of the 45 switch operating lever, coil spring, and its guide pin;

Fig. 6 is a perspective of the combined supporting bridge and switch frame; and

Fig. 7 is a perspective of the switch blade yoke.

For the purpose of illustrating the invention, I have embodied it in a flush wall switch, but it will be understood that many of the features are applicable to switches of other types, and that the invention is 55 not limited to an installation of the par-

ticular type shown. The cup-shaped insulating body 10 of the flush switch is supported in a receptacle (not shown) by a bridge piece 11 extending beyond the opposite ends of the switch body and secured 60 to the latter by screws 12 taking into tapped holes 13 in the bridge. Adjacent the latter are holes 14 tapped to receive the screws 15 by which the face plate 16 is mounted 65 in the usual fashion.

At the four corners of the switch body are binding screw terminals 17, 18, 19 and 20 arranged on depressed ledges and having wings extending into the switch chamber to form switch contacts. The arrangement of these contacts may be as desired 70 to effect any preferred current distribution. As shown, there are two high and two low contacts 21 and 22, respectively. The contact wings 21 and 22 of the terminals 75 are offset substantially at right angles to the terminal plates, and from the margins of the latter adjacent the side walls of the switch chamber. The wings lie in planes parallel to said side walls, and the free 80 ends which form the contacts proper, which are engaged by the cooperating switch blades, are inwardly offset in pairs into alignment longitudinally of the switch. The wings of the high contacts 21 rise from the terminal plates and assist in boxing-in 85 stray beards from the wires secured beneath the binding screws. The wings of the low contacts pass downward in channels 23 formed by shoulders 24 spaced slightly from 90 the side walls of the switch chamber. The free ends of the low contacts are angled over the shoulders 24 and supported thereon. In the construction shown the terminals 18 and 19 at one end of the switch 95 are united by a cross strap 25 let into the base of the receptacle and electrically connected, as well as mechanically secured in position by the screw bolts 26 and 27 which secure the terminals upon the base. 100 The switch is thus a double-bladed single-pole switch having three branch connections. The switch may be wired, however, and used as a double-pole switch, in which case the strap 25 would be omitted. It 105 may also be used as a single-pole, single-bladed switch by omitting certain of the switch contacts.

Within the body chamber 28, the switch mechanism is mounted upon the frame plate 110

29, preferably integral with the supporting bridge 11. In order to locate the plate 29 substantially in the longitudinal mid plane of the switch chamber, and also in the mid 5 plane of the bridge itself, the latter is notched at 30. The switch-operating lever comprises legs 31 which straddle the frame plate and embrace it sufficiently closely to prevent any objectionable cross play of the 10 lever thereon. At its outer end the lever carries a thumb piece 32 having wings 33 which serve to obturate the hole in the cover plate through which it passes, and thus to prevent the entry of dust and dirt 15 therethrough into the switch chamber. Notches 34 in the upper edge of the plate 29 accommodate the wings 33 of the thumb piece in the extreme angular positions of the lever.

20 The lever pivots on a pin 35 which passes freely through registering holes 36, pierced respectively in the frame plate and legs 31 of the lever. At the inner ends of the latter are formed notches 37 to receive the head 25 38 of guide pin 39 for the switch operating coil spring 40. Lugs 41 on the head of the pin straddle the lever legs to hold the pin against lateral escape, while the outward offsetting of the lower ends of the legs at 42 30 spaces the latter sufficiently far apart to clear the adjacent end of the coil spring. In assembled position the head 38 of the guide pin underlies the lower edge of the frame plate 29, and the pin 39 works substantially in the plane of the plate.

35 Intermediate the bearing holes 36 and the notched ends of the lever legs are laterally extending bays 43 having arcuate central apertures 44 to accommodate the bearing pin 45 on which the switch yoke 46 rocks. This bearing pin has a reduced central portion 47 of a length substantially corresponding to the thickness of the plate 29. To permit the pin to be positioned in the frame plate 40 45, the latter has a bayonet opening 48 formed therein, the larger portion thereof having a diameter slightly exceeding the greatest diameter of the bearing pin. In the reduced portion of the opening 48 is 50 a bearing notch 49 to receive the central reduced area 47 of the bearing pin. The latter is introduced into position by passing it through the larger portion of the opening 48 and shifting it laterally until the 55 reduced area 47 drops into the bearing notch 49. At its outer ends the bearing pin is shouldered to form trunnions 50 upon which the switch yoke rocks and by which it is centered.

60 The switch yoke is preferably struck from sheet metal angled to shape. Bayonet slot bearing notches 51 formed in the legs of the yoke may be readily mounted on the bearing pin by passing the yoke upward from beneath the frame plate, with the yoke legs

straddling the latter, and then manipulating the yoke to hook the bearings on the trunnion ends 50 of the pin. The web of the yoke is apertured at 52 to receive the guide pin 39 and the constant pressure of the 70 spring 40 against the web of the yoke not only maintains the latter in engagement with the trunnions 50, but also holds the reduced portion 47 of the pin seated in the notch 49 in the switch frame.

75 The switch blades 53 are riveted to the legs of the switch yoke, but insulated therefrom by suitable bushings 54. It will be noted that in assembled position, the trunnions of the bearing pin lie substantially in the longitudinal plane passing through the opposite ends of the switch bar. It will also be noted that the axes of oscillation of the switch lever and switch yoke are spaced only a slight distance apart, and that they are 80 arranged close to the plane of the supporting bridge. As a consequence the switch blades are held high on the frame, and it is thus possible to use a shallow switch body to house the contacts and switch mechanism, without sacrificing current breaking capacity. The spacing of the yoke arms is such that in assembled position the inner 85 ends of the upper rivets, which play across the axis of the pin 35, prevent the escape of the latter from the holes 36 in the lever and frame.

90 At opposite sides of the pierced web of the yoke are offset flanges 55 which impinge against the downwardly extending stop legs 56 and 57 of the frame plate, and thus limit the throw of the switch yoke.

95 In order to insure a positive initiation of the opening and closing movements of the switch blades, I pivot cam levers 58 and 59 100 at 60 and 61 on the legs 56 and 57 of the switch frame. The upper ends 62 of the levers lie in the path of the bays 43 of the legs of the operating lever. The lower ends 105 of the levers 58 and 59 are so positioned that when their upper ends 62 are engaged by one or the other of the bays of the switch lever 31, they are forced into the area between the stop legs 56 and 57 of the frame. Consequently, when the switch lever is 110 swung on its arc, one or the other of the bays 43 engages one or the other of the cam levers 58 or 59 and forces its lower end against one of the stop wings on the web of the yoke 46, thus positively forcing the latter out of its stop position and initiating the throw 115 of the switch yoke which is completed by the biasing action of the toggle spring 40. The latter may be made lighter than would be otherwise necessary in order to overcome the frictional drag between the switch blades and the switch contacts in the closed 120 position of the switch.

125 Stop pins 63 lying in the path of the upper ends of the cam levers, limit the throw of 130

the latter, which thus form stops which limits the throw of the switch lever.

To exclude dirt from the switch chamber, I provide in addition to the usual face plate, a cover plate 64 of fiber, paper, or the like, which overlies the switch chamber and rests upon ledges 65 at opposite sides thereof, and upon the end barrier ribs 66 which are interposed between the pairs of contacts at opposite ends of the switch chamber. Tongues 67 formed at the opposite ends of the cover 64 may be passed under the bridge 11, the tongues preferably being so located as to engage beneath the bridge at the notches 30 at opposite ends of the frame web 29. A central aperture 68 in the cover accommodates the thumb piece 32, which passes therethrough to operating position above the face plate 16.

20 The operation of the switch is readily understood. Assuming it to be in the circuit closing position shown in Fig. 2, the upward movement of the thumb piece 32 swings the operating lever on its axis 35, 25 and thus moves the head 38 of the spring guide pin 39 across the axis of oscillation of the switch bar yoke. As the head of the pin 38 is moving toward the axis of oscillation, the bay 43 on the switch lever engages the upper end 62 of the cam lever 58 and swings the lower end into engagement with the flange 55 of the switch yoke, thus forcing the latter away from its stop position against the leg 56 of the frame. 30 This positively frees the switch blades 53 from the stationary switch contacts and the spring 40 immediately thereafter biases the switch bar yoke with a snap action to open-circuit position. The switch yoke is now 35 halted by its impingement against the leg 57, while the operating lever is halted by the impingement of the upper end 62 of the cam lever 58 against its stop pin 63. The switch-closing movement involves the same 40 movements, but in the opposite direction.

Various modifications in detail of construction which do not depart from what I claim as my invention, will readily occur to those skilled in the art.

50 I claim—

1. An electric switch comprising a chambered insulating body, a sheet metal supporting bridge therefor, a single frame plate integral with said bridge and offset at substantially right angles thereto, and extending into the chamber of said insulating body, and a switch mechanism mounted on said frame plate and comprising an oscillating member straddling the upper margin of the plate, and a second oscillating member straddling the lower margin of the plate.

2. An electric switch comprising a chambered insulating body, a sheet metal supporting bridge therefor, a frame plate integral with said bridge and offset at substan-

tially right angles thereto, and extending into the chamber of said insulating body, and a switch mechanism mounted on said frame plate, said mechanism comprising a switch operating lever having lugs straddling said frame plate. 70

3. An electric switch comprising a chambered insulating body, a sheet metal supporting bridge therefor, a frame plate integral with said bridge and offset at substantially right angles thereto, and extending into the chamber of said insulating body, and a switch mechanism mounted on said frame plate, said mechanism comprising a switch operating lever having lugs straddling said frame plate, together with a switch bar yoke straddling the frame plate. 75

4. In an electric switch, an insulating body, a bridge mounted thereon and comprising at its opposite ends supporting lugs and an intermediate frame plate integral therewith but lying in a plane substantially at right angles to said lugs and forming the sole connecting bond therebetween, an insulating cover arranged above said bridge, 80 and tongues integral with said cover engaged beneath the supporting lugs of the bridge adjacent said offset frame plate. 85

5. An electric switch comprising a cup-shaped insulating body, a supporting bridge spanning the open face of said body, and an insulating cover resting on said body and having tongues freely engaged beneath said bridge, said bridge being notched to receive 90 said tongues. 95

6. In an electric switch, an apertured frame plate, a shouldered pin freely entering said aperture and having a reduced area between its shoulders substantially co-extensive with the thickness of said plate and lying in the plane of the latter in assembled position, a switch element pivoted on said pin, and a spring engaging said member and serving to hold the pin in said aperture with its shoulders arranged on opposite sides of 100 the plate. 105

7. In an electric switch, a frame plate, a switch member pivoted on said frame plate on an axis substantially at right angles to the latter, said axis comprising a pin extending on opposite sides of the plate and having shoulders forming abutments engaging opposite faces of the plate, said plate being pierced to accommodate said pin at its point of greatest diameter. 115

8. In an electric switch, a frame plate having an aperture, and a bearing notch of less diameter communicating with said aperture, in combination with a bearing pin having a portion of reduced diameter intermediate its ends, said pin being adapted to pass through said aperture in the frame plate, and having its portion of reduced diameter resting in said bearing notch in the assembled position of the parts. 120

125

130

9. In an electric switch, a frame plate, a pivot pin piercing said plate at substantially right angles, and shouldered at its opposite ends, in combination with a switch member pivoted on the reduced ends of said pin beyond said shoulders.
10. In an electric switch, a frame plate, a pivot pin freely seated in said plate and extending on opposite sides of the latter, a switch member straddling the plate and journalled on said pivot pin, and spring means engaging said switch member and stressing the latter in a direction to maintain said pivot pin seated in the plate.
11. In an electric switch, a frame plate, a switch operating lever straddling said plate and journalled thereon, an oscillating switch yoke also straddling the plate and supported thereon, in combination with a switch operating spring lying in the plane of the plate and operatively interposed between said lever and switch yoke.
12. In an electric switch, a frame plate, a cam lever pivoted thereon, a switch operating bar straddling the plate and pivoted thereon, a toggle spring operatively interposed between said lever and yoke, said cam lever being engaged by said switch operating lever during its oscillation, and moved by the latter into engagement with the switch yoke to initiate the oscillation of the latter.
13. In an electric switch, an insulating body, a bridge mounted thereon and comprising at its opposite ends supporting lugs and an intermediate frame plate integral therewith but lying in a plane substantially at right angles to said lugs and forming the sole connecting bond therebetween.
14. In an electric switch, a cup-shaped insulating body, a bridge piece spanning the open face thereof, and having a frame plate integral therewith and offset into the switch chamber, said bridge having a reduced area between its opposite ends and the frame portion, together with an insulating cover overlying said bridge and having tongues engaging beneath the reduced area thereof to hold the cover in position.
15. In an electric switch, a frame plate having stop members at one margin, a member pivoted on said plate and oscillating between said stop members, a cam lever mounted on said plate and movable at one end into the area between said stop members, in combination with a rock lever pivoted on said plate and engaging said cam lever to force said end thereof into the area specified and against the oscillating member, for the purpose set forth.
16. In an electric switch, an insulating body recessed to afford a switch chamber having an end wall provided with a relatively narrow channel adjacent the side wall of the chamber, an integral sheet metal wire terminal and switch contact supported on said base and comprising a wire terminal plate mounted outside the switch chamber, a leg offset from one of the side margins of said plate substantially at right angles to the latter and having a portion thereof arranged in said channel in the end wall of the switch chamber, and a contact wing offset from the lower portion of said leg and extending into the switch chamber, the leg and contact wing being arranged in substantially parallel planes.
17. In an electric switch, a cup-shaped insulating body, a depressed corner ledge thereon, the end wall of the chamber of said insulating body having a narrow channel extending in the direction of the depth of the cup and leading to one side of the ledge, in combination with a wire terminal plate mounted on said ledge and having a leg offset from the side thereof and entering said channel, together with a contact wing extending from the end of said leg and offset therefrom into the switch chamber.
18. In an electric switch, a cup-shaped insulating body having in its end wall a narrow channel extending in the direction of the depth of the cup and adapted to receive and confine at least a portion of a wire terminal leg, the portion of the end wall adjacent said channel forming a shoulder adapted to support a contact wing, in combination with a combined wire terminal and switch contact element formed from sheet metal and comprising a down leg guided in said channel and a contact wing offset from said down leg and bearing against said shoulder for support.
- In testimony whereof I have signed my name to this specification.

CARL ERIC ANDERSON.

Certificate of Correction.

It is hereby certified that in Letters Patent No. 1,532,855, granted April 7, 1925, upon the application of Carl Eric Anderson, of Stratford, Connecticut, for an improvement in "Electric Switches," errors appear in the printed specification requiring correction as follows: Page 2, line 104, for the misspelled word "openng" read *opening*; page 3, line 2, for the word "limits" read *limit*; page 4, line 26, claim 12, after the word "thereon" insert the words and comma *a switch yoke straddling the plate and pivoted thereon*; and that the said Letters Patent should be read with these corrections therein that the same may conform to the record of the case in the Patent Office.

Signed and sealed this 12th day of May, A. D. 1925.

[SEAL.]

KARL FENNING,
Acting Commissioner of Patents.
